DUAL SEAL CLOSURE

Carroll P. Krupp, Barberton, Ohio, assignor to
The B. F. Goodrich Company, New York, N. Y.,
a corporation of New York

Application December 11, 1947; Serial No. 791,076

11 Claims. (Cl. 24—205.1)

1

The invention relates to closures for sealing adjacent margins and especially to dual-seal closures utilizing slide fasteners.

It is an object of the present invention to provide an improved closure structure having increased reliability of the seal under all conditions of flexure encountered in use of the closure and utilizing to a maximum the advantages of the lip-sealing principle. Other objects of the invention are to provide for a double lip-sealing action at one face of the closure; to provide for maintaining the seal despite bending, twisting and flexure of the margins; to provide closure means including flexible sealing elements inherently maintained in overlapping, intercalated relation one to another in the closed condition of the closure; and to provide for simplicity of construction and effectiveness of operation.

Further objects of the invention are to provide for mounting sealing members at the margins in a manner to effect sealing of the latter at two spaced-apart positions laterally of the closure while the members undergo intercalating movement relative to one another; to provide for assuring the positioning of the sealing members in intercalated relation one to another; to provide for guarding against accidental breakage of the seal and separation of the members; and to provide for conveniently opening and closing the closure.

These and other objects and advantages of the invention will be apparent from the following description.

In the drawings which form a part of this specification and in which like numerals are employed to designate like parts throughout the same,

Fig. 1 is a plan view showing a sealing closure attached to separable margins of an article to be fastened, and constructed in accordance with and embodying the invention, parts being broken away,

Fig. 2 is a sectional view taken along line 2—2 of Fig. 1,

Fig. 3 is a sectional view taken along line 3—3 of Fig. 1,

Fig. 4 is a sectional view taken along line 4—4 of Fig. 1,

Fig. 5 is a cross-sectional view of the closure of Fig. 1 showing the closure in the open condition with sealing members in disengaged and separated relation one to another, broken lines indicating the flexed position of the sealing members for the engaged and closed relation thereof,

Fig. 6 is a perspective view from above of a runner for the closure,

Fig. 7 is a side elevation of the runner, and

Fig. 8 is a sectional view taken along line 8—8 of Fig. 7.

In the illustrative form of the invention shown

in the drawings, the closure construction includes joining means, preferably a slide fastener structure, for separably uniting adjacent margins 15, 16 of an article to be fastened, which slide fastener structure has flexible margins or stringers 17, 18 of woven fabric or other suitable material. The stringers may have a substantially impervious coating or impregnation 19, 19 of resilient rubber or other rubber-like material at a face of the stringers. Beads 20, 21 of cord or other suitable material extend along the adjacent marginal edges of the stringers 17, 18 at each face thereof, and are suitably attached as by stitches engaging the cords and the stringers. Opposing series of cooperating fastener elements or teeth 22, 23 are securely anchored at the marginal beaded edges and include engaging portions 24, 25 and mounting portions 26, 27. The teeth are spaced-apart longitudinally of the stringers providing zones 28, 29 between the engaging portions of adjacent teeth.

For closing and sealing the adjacent margins, a pair of closing and sealing members 30, 31 of flexible strip material such, for example, as resilient rubber or other rubber-like material are mounted adjacent the beaded edges of the stringers at a face of the closure. Although the members 30, 31 may be mounted on the stringers closely adjacent the teeth, the members are preferably mounted directly on the mounting portions 26, 27 of the teeth 22, 23, as shown in the drawings, to resist objectionable displacement of the members with respect to the teeth. The members may be molded upon the teeth and adhered thereto by a vulcanized bond, and extend continuously along the stringers bridging the spaced-apart teeth. The zones 28, 29 between the engaging portions 24, 25 of the teeth are free of the rubber material of the members so that relative movement of the teeth for opening and closing the fastener structure will not be objectionably restricted. In the lip-sealing relationship, as shown in the drawings, especially Fig. 2, a portion of one side face of the element adjacent the edge of the element contacts and seals against the sealing surface, and this action is facilitated by the clearance whereby a portion of the other side face extending away from said edge is out of contact with adjoining structure, and by the clearance preferably between portions of the element and the sealing surface rearwardly of said edge.

The closing member 30 includes a pair of elements or marginal portions 32, 33 in overlying, outwardly aligned and spaced-apart relation one to another, each projecting toward the other margin 17 for disposition in an overlapping, intercalated relation with a third element 34 or projecting marginal portion of the sealing member 31 at said other margin 17. The portions 32, 33

and the portion 34 are each of resilient rubber-like material and project laterally of the stringers toward each other from base portions 35, 36 of the members 30, 31, which base portions may be in continuation of the rubber coatings 19, 19 and are mounted directly on the teeth 22, 23 for bracing the members and for facilitating maintenance of the desired positioning of the members.

Each marginal portion 32, 33, 34 tapers gradually to a thin edge at 37, 38, 39 as shown especially in Fig. 5, for effecting sealing by lip-action. By lip-action is meant a sealing action effected by a flexible sealing element, the edge of which may be termed a lip, which is in contact with and preferably pressed against a sealing surface so as to seal effectively at low pressure differences approaching zero and also at high pressure differences.

The pair of tapered marginal portions 32, 33 are constructed and arranged so that they provide an inclined open-faced slot 40 having generally parallel sides in the member 33, the slot 40 facing toward the sealing member 31 and being dimensioned sufficient to receive a substantial part of the tapered marginal portion 34 for the closed condition of the closure.

The inner marginal portion 32 nearest or adjacent the teeth 22, 23 presents an outwardly inclined sealing surface 41 constituted by one of the sides of the narrow slot 40 and oppositely inclined relative to a sealing surface 42 of the marginal portion 34, that is the surfaces 41 and 42 diverge laterally away from one another and outwardly with respect to the adjacent faces of the teeth 22, 23. When the marginal portion 34 is inserted in the slot 40 under the engagement of the teeth, the edge at 37 slidably contacts the sealing surface 41 in sealing relation therewith by lip-action of the edge and presses resiliently against the surface 41 under flexure of the marginal portion 34 substantially to the position shown by broken lines in Fig. 5.

Coincidentally with the positioning of the portion 34 in the slot 40, the edge at 38 of the outer marginal portion 33 slidably contacts the sealing surface 42 of the portion 34 in sealing relation therewith by lip-action of the edge and presses resiliently against the surface 42 under flexure of the marginal portion 33 substantially to the position shown by broken lines in Fig. 5. The arrangement is such that the closing member 30 and the sealing member 31, for the closed condition, effect a double lip-sealing action at positions spaced-apart laterally of the margins at one face of the closure and continuously along the margins. In the closed condition the respective tapered marginal portions of the members are in overlapping, intercalated relation one to another, as shown especially in Figs. 1 and 2, with their edges 37 and 38 each pressing resiliently in the same general direction toward the stringers by flexure of the edge against the sealing surface of the other member, thereby providing effective sealing by both elements under dominant fluid pressure at this face of the closure.

The members 30, 31 are constructed and arranged as shown in the drawings to provide hinging zones at 43, 44 at the junction of the marginal portions 33, 34 with the base portions 35, 36 for permitting resiliently restrained, swinging movement of the portions 33, 34 during engagement of the slide fastener structure, thereby promoting flexure of the portions 33, 34 and lip-action sealing by the same at the respective sealing surfaces 41, 42.

For avoiding accidental breakage of the seal,

especially at the edge at 38 in contact with the sealing surface 42, the closing member 30 has an upper rounded or shoulder portion 45 in continuation of the upper tapered marginal portion 33, which rounded portion 45 projects above the opposite sealing member 31 including the sealing surface 42. This arrangement supplements the guarding of the seal effected by the overlapping, intercalated relation of the members 30, 31, and especially prevents breakage of the lip-seal between the marginal portion 33 and the sealing surface 42 by accidental separation of such portion and surface even under substantial twisting, flexure and bending of the stringers 17, 18.

The lower or inner marginal portion 32 of the closing member 30 and the marginal portion 34 of the sealing member 31 are spaced-apart from the adjacent faces of the teeth 22, 23 providing space therebetween for the passage of an upper plate 46 of a runner or slider 47 for engaging and disengaging the teeth by sliding movement along the stringers 17, 18.

The runner may be made of bronze or other suitable material of suitable strength and durability characteristics. The runner has the upper plate 46 and a lower flanged plate 48 interconnected by a center-post 49 of streamline shape in cross-section integral with the plates at the opening end at 50 of the runner providing with the upper and lower plates suitable diverging channels for the passage of the teeth 22, 23.

The upper surface of the plate 46 has longitudinally extending side portions 52, 53 inclined downwardly toward the lower plate 48 and toward the closing end at 51 and merging at such closing end for contacting and guiding the marginal portions 32 and 34 of the members 30, 31. The side portions also merge with rounded end portions 54, 55 of the upper plate. The lower plate may have an apertured extension 56 for the attachment of a suitable pull-tab (not shown) for manipulating the runner. The construction facilitates intercalating the closing and sealing members and smoothness of sliding movement of the runner.

The sealing closure described hereinabove is useful for closing an opening in a wall of an article such, for example, as a boot or other footwear, a tent, sleeping bag, inflatable suit for aviators, and other related articles. To this end, the closure may be mounted at a face of the wall of the article so that the closing and sealing members 30, 31 extend through the opening and are disposed at the other face of the wall, as shown especially in Fig. 1.

The stringers 17, 18 may be adhesively attached as by rubber-cement 56 of the air-curing type to the adjacent margins 15, 16 at the opening in the wall. The margins 15, 16 may extend to the members 30, 31 and a strip of tape 57 of suitable water-tight, flexible fabric material may extend continuously along the outer edges of the stringers in overlapping relation to the same for assuring continuity of sealing. The tape may be adhesively attached as by a suitable rubber-cement 56.

The members 30, 31 at the closing end at 58 of the closure have their end portions 30a, 31a cemented together in overlapping, intercalated relation, as shown especially in Fig. 4, and a strip 59 of suitable tape is adhered thereover in overlapping relation therewith to assure sealing at the closing end at 58.

The members 30, 31 and the stringers 17, 18 at the opening end at 60 of the closure have their end portions 30b, 31b and 17a, 18a, respec-

tively, spread-apart laterally and retained in this disposition by an integral top stop structure 62 of H-shape in cross-section and suitable material, as shown especially in Figs. 1 and 3, to accommodate and hold the runner 47 inwardly of the ends of the members 30, 31, the end portions 30b, 31b of the members being slightly enlarged and adhered together at the top stop 62 in overlapping, intercalated relation to one another, as shown especially in Fig. 3. A strip 64 of suitable tape is adhered in overlapping relation to the end portions 30b, 31b. This arrangement assures sealing at the opening end at 60 of the closure.

For the closed condition of the closure shown in Fig. 1, the runner is manipulated toward the closing end at 58 to disengage the teeth 22, 23 and spread-apart the stringers 17, 18, thereby separating the closing and sealing members substantially to the position shown in Fig. 5 and opening the closure.

Moving the runner toward the opening end and into contact with the top stop 62 at 60 engages the teeth and draws the stringers together progressively. The members 30, 31 are coincidentally and progressively drawn together, the inclined side portions 52, 53 of the upper plate 46 guiding the members so that the marginal portion 34 is intercalated in the slot 40 between the spaced marginal portions 32, 33. The members 30, 31 are thus disposed in the desired overlapping and contacting arrangement effecting the double lip-seal at laterally spaced positions of the members 30, 31 assuring maintenance of the lip-sealing action of the edges in contact with the sealing surfaces despite twisting, flexure and bending of the margins of the closure. The hereinabove described construction providing the overlapping, intercalated relation of the members 30, 31 prevents effectively separation of the members and accidental breakage of the seal under flexure conditions.

Variations may be made without departing from the scope of the invention as it is defined in the following claims.

1. Claim:

1. A sealing closure for adjacent margins, said closure comprising separable fastener elements at said margins for detachably uniting the same, a sealing member at one of said margins having a marginal portion of resilient rubber-like material projecting toward the other margin, said portion presenting a sealing surface and tapering to an edge, and a closing member at said other margin having a pair of marginal portions of said rubber-like material overlying one another in spaced-apart relation and projecting toward said sealing member for closing said margins by an overlapping intercalated relation of all said portions, one marginal portion of said pair having a sealing surface for contact by lip-action with said edge of said sealing member in the closed condition, and the other marginal portion tapering to an edge for contact by lip-action with said sealing surface of said sealing member in said closed condition, the construction and arrangement being such that the edges of said members in said closed condition are each disposed to flex resiliently against the sealing surface of the other member with the directly opposed faces of said members adjacent such edge in spaced-apart relation to one another.

2. A sealing closure for adjacent margins, said closure comprising a sealing member of resilient material at one of said margins projecting to-

ward the other margin and tapering gradually to a thin edge and having a sealing surface on said sealing member extending rearwardly from said edge, and an additional sealing member of resilient material at said other margin having a groove facing toward said sealing member with spaced-apart faces of said groove in overlapping relation for receiving therebetween said sealing member in the closed condition of the closure, one of said faces of said additional sealing member extending to an edge and the other of said faces thereof providing a sealing surface, the edges of said sealing members in said closed condition each being disposed to press resiliently in the same general direction by flexure of the edge against the sealing surface of the other member with portions of each of said faces of said groove in spaced-apart relation to said sealing member first mentioned, and separable fastener means on said margins for separably joining said margins with said sealing members disposed in sealing relation one to the other.

3. A sealing closure for adjacent margins, said closure comprising a sealing member of resilient material at one of said margins projecting toward the other margin and terminating in an edge, and an additional sealing member at said other margin having portions of resilient material providing a slot facing toward said sealing member with opposing spaced-apart faces of said slot in overlapping relation for receiving therebetween said sealing member in the closed condition of the closure, one of said spaced-apart faces of said additional sealing member extending to an edge for sealing contact with said sealing member in said closed condition and being in spaced-apart relation to an overlapping portion of said sealing member in said closed condition, and separable fastener means on said margins for separably joining said margins with said sealing members disposed in sealing relation one to the other.

4. A sealing closure comprising a pair of margins, a strip sealing structure at one of said margins having resilient elements providing spaced-apart overlapping faces defining a groove therebetween, and a member at the other margin of said pair shaped for disposition in said groove and having an edge for sealing contact with one of said faces while out of contact with the other of said faces in the closed condition of the closure, said other of said faces terminating in an edge for disposition in sealing relation with a surface of said member in said closed condition, and slide fastener means for separably joining said margins with said strip sealing structure and said member disposed in their sealing relation in said closed condition.

5. A sealing closure comprising a pair of margins, a pair of strips at said margins each having a resilient element which projects laterally toward the other strip and each terminates in a sealing edge, a sealing surface overlapping and spaced from the projecting element of the first of said pair of strips, the resilient element of the second strip of said pair in the closed condition of the closure having its sealing edge engageable with said sealing surface and having a face thereof engageable with the sealing edge of the first strip while portions of said sealing surface and said face adjacent the sealing edges are spaced from adjoining structure, and slide fastener means for separably joining said margins and for manipulating said pair of strips into said closed condition.

6. In a sealing closure having a pair of stringers and cooperating teeth separably joining said stringers in the closed condition of the closure, in combination therewith, a strip including a first resilient element at one of said stringers, a strip including a second resilient element at the other stringer, each resilient element projecting laterally toward the other strip and terminating in a sealing edge and said second resilient element presenting a face to the sealing edge of said first resilient element, a sealing surface overlapping and spaced from said first resilient element, said sealing surface and said face of said second resilient element in the closed condition having an inclined disposition relative to one another and to said stringers, said second resilient element in said closed condition having its sealing edge engageable with said sealing surface and its inclined face engageable with the sealing edge of said first resilient element while portions of said sealing surface and said inclined face adjacent the sealing edges are spaced from adjoining structure, and a slider engaging said teeth for manipulating said stringers into the closed condition with said strips in their sealing relation.

7. In a sealing closure having a pair of stringers and cooperating teeth separably joining said stringers in the closed condition of the closure, in combination therewith, a strip including a first resilient element at one of said stringers, a strip including a second resilient element at the other stringer, each resilient element projecting laterally toward the other strip and terminating in a sealing edge and said second resilient element presenting a face to the sealing edge of said first resilient element, a sealing surface overlapping and spaced from said first resilient element, said sealing surface and said face of said second resilient element in the closed condition diverging outwardly relative to one another and to said stringers, said second resilient element in said closed condition having its sealing edge engageable with said sealing surface and having said face thereof engageable with the sealing edge of said first resilient element while portions of said sealing surface and said face adjacent the sealing edges are spaced from adjoining structure, and a slider engaging said teeth for manipulating said stringers into the closed condition with said strips in their sealing relation.

8. A sealing slide fastener closure comprising a pair of stringers, a strip sealing structure at one of said stringers having resilient elements providing spaced-apart overlapping faces defining a groove therebetween, a member at the other stringer of said pair shaped for disposition in said groove and having an edge for sealing contact with one of said faces while out of contact with the other of said faces in the closed condition of the closure, said other of said faces terminating in an edge for disposition in sealing relation with a surface of said member in said closed condition, and means including a slider and fastening elements for separably joining said stringers and manipulating said strip sealing structure and said member into their sealing relation in said closed condition.

9. A sealing slide fastener closure comprising a pair of stringers, a pair of strips at said stringers each having a resilient element projecting laterally toward the other strip and each terminating in a sealing edge, a sealing surface overlapping and spaced from the projecting element of the first of said pair of strips, the resilient element of the second strip of said pair in the closed

condition of the closure having its sealing edge engageable with said sealing surface and having a face thereof engageable with the sealing edge of the first strip while portions of said sealing surface and said face adjacent the sealing edges are spaced from adjoining structure, and means including a slider and fastening elements for separably joining said stringers and manipulating said strips into their sealing relation in said closed condition.

10. A sealing closure comprising a pair of flexible stringers having slide fastener elements and a slider for separably joining the stringers, and a strip of resilient rubber-like material on each of the stringers, one of the strips having a first element of the resilient material tapering to an edge and a second element of the resilient material having a sealing surface spaced from and overlapping said first element providing therebetween a slot open toward the other strip, said other strip on the other stringer having a third element of the resilient material tapering to an edge toward the first strip, said third element in the closed condition of the closure being disposed in said slot with said edge thereof in sealing contact with said sealing surface of said second element and having a face thereof in sealing contact with said edge of said first element while being otherwise out of contact with said first element.

11. A sealing closure comprising a pair of flexible stringers having cooperating teeth and a slider for separably joining the stringers, a strip of resilient rubber-like material mounted directly on the teeth of one of said stringers and having a protecting shoulder spaced from the stringer, said strip including a first element of the resilient material projecting laterally away from said shoulder in spaced-apart overlying relation to the stringer and tapering to an edge, and said strip including a second element of the resilient material between said first element and said stringer having a sealing surface spaced from and overlapping said first element providing therebetween a slot open toward the other stringer, and an additional strip of the resilient material mounted directly on the teeth of said other stringer having a third element of the resilient material tapering to an edge toward the first strip and having an overall height relative to said other stringer less than that of said first strip including said protecting shoulder, said third element in the closed condition of the closure being disposed in said slot with said edge of said third element in sealing contact with said sealing surface of said second element and with a face of said third element in sealing contact with said edge of said first element while being otherwise out of contact with said first element.
